AUTOMOTIVE IGNITION CONTACT POINTS

Frank Skay, Detroit, Mich., assignor to Holley Carburetor Company, Detroit, Mich., a corporation of Michigan

Application July 12, 1952, Serial No. 298,496

3 Claims. (Cl. 200—166)

2

R and O are two slots in N to permit the bracket N to be adjusted around its insulated pivot Q which locates on the plate S.

The Figures 3 and 4 show a stationary positive contact H with cavity L mounted on bracket C of entire bracket N.

J is the negative contact mounted on the breaker arm E.

Figure 5 shows the direction of transfer of the metal when the contact H (stationary) is positive.

Figure 6 shows the direction of transfer of the metal when the moving contact A is positive.

Operation

15 1. The movement of the arm forces air into the cavity, cushioning the impact of the two contacts; and

2. At the same time provides cooling.

3. Tungsten metal transfer from the cavity side prevents any confined central interference such as a high area within a cavity.

4. Pressure created in the center of the contacts when closed reduces arcing when they break.

What I claim is:

1. A pair of positive and negative contacts for an ignition system for an internal combustion engine comprising a stationary contact point and a moving contact point, one point being plus and the other point being minus, a pre-formed cavity in the positive contact point the cavity being so formed that it traps air in and expels air from the cavity at the moment of making contact and provides a substantial area of contact, the other contact point being flat and both being unperforated.

25 2. A combination of contacts as set forth in claim 1 in which the positive contact having the cavity is the moving contact of the pair.

3. A combination of contacts as set forth in claim 1 in which the positive contact having the cavity is the stationary contact of the pair.
